UNITED STATES PATENT OFFICE

ANTHONY J. STOUGES, OF QUEENS VILLAGE, NEW YORK, ASSIGNOR TO MERGENTHALER LINOTYPE COMPANY, A CORPORATION OF NEW YORK

TYPOGRAPHICAL MACHINE

Application filed January 4, 1930. Serial No. 413,466.

This invention relates to typographical machines, such as linotype machines of the general organization represented in U. S. Letters Patent to O. Mergenthaler No. 436,532, wherein circulating matrices are released from a magazine in the order in which their characters are to appear in print and then composed in line, the composed line transferred to the face of a slotted mold, the mold 10 filled with molten metal to form a slug or linotype against the matrices which produce the type characters thereon, and the matrices thereafter returned through distributing mechanism to the magazine from which they 15 started.

In these machines, the transfer of the composed lines to the casting mechanism is effected by a so-called "line delivery carriage" which comprises a slide or body portion and 20 a pair of vertical opposed line engaging fingers, one of said fingers (the right-hand one) being short and fixed to the slide, and the other (the left-hand one) being long and movable relatively thereto. Ordinarily, the 25 long left-hand finger is rigid throughout, but in the present embodiment, it is provided with a lower hinged section which, for reasons later to appear, is capable of yielding laterally away from the opposing finger. While 30 such a two-part left-hand finger is admittedly old in the art, the present invention contemplates certain improvements which are intended to give the finger greater strength and durability in order that it may better 35 withstand the shocks and rough usage to which it is constantly subjected in practice.

To this end, the two sections of the improved finger are fitted together by an elongated tongue-and-slot connection presenting 40 cooperating bearing and banking surfaces located both above and below the axis of the hinge. In the preferred embodiment illustrated, the tongue is formed on the upper fixed section of the finger, from which it depends, and at its lower end is beveled off to afford an additional banking surface below 45 the hinge for locating the lower hinged section of the finger in its normal vertical position, while said lower section is slotted to 50 receive the tongue and has its upper end on

opposite sides of the slot beveled off to cooperate with banking surfaces formed at the lower end of the fixed section and located above the hinge. Certain other improvements in the construction of the finger are 55 also contemplated, but these will best be understood from the detailed description to follow.

In the accompanying drawings, the invention is shown merely in preferred form and by way of example, and obviously many changes and variations may be made therein and in its mode of application which will still be comprised within its spirit. It should, therefore, be understood that the invention is not limited to any specific form or embodiment except insofar as such limitations are specified in the claims.

Referring to the drawings:

Fig. 1 is a front elevation of a portion of a 70 linotype machine equipped with the present improvements;

Fig. 2 is a fragmentary front view, showing the line transfer carriage in the course of its return movement and depicting the relation which the left-hand finger bears to a justified line;

Fig. 3 is a perspective view of the improved left-hand finger and its supporting block; and

Fig. 4 is a perspective view, partly broken away, of said finger detached.

The matrices X, when released from their storage magazine (not shown), are delivered in the usual way to the assembling elevator A, wherein they are composed in line, together with the spacebands Y, under the influence of the star wheel A¹. After composition, the elevator A is raised into registration with the intermediate channel B and the composed line positioned between the long and short fingers of the delivery slide C, which then carries the line through said channel and into the casting elevator D. The elevator D thereupon descends to present the composed line between the clamping jaws E for the slug casting operation, the line being justified before casting by the vertically movable bar F, which in rising is adapted to drive the spacebands upwardly through the 100

- line so as to expand it against the jaws (see Fig. 2). The foregoing parts and their mode of operation are so well known that any further description would be superfluous.
- 5 The line delivery slide C (Figs. 1 and 2) is mounted in the guideway O¹ of the machine frame O and is moved to and fro by the power-operated lever G and the intermediate connecting link G¹. The short right-hand finger C¹ is rigidly secured to the delivery slide C, whereas the long left-hand finger C² is movable relatively thereto, being attached to a separate block C³ which is also slidably mounted in the guideway O¹.
- 10 In order to prevent damage to the spacebands Y, which are occasionally projected by the justification bar F into the path of the long left-hand finger C² during the return movement of the slide C (see Fig. 2), said finger is provided with a lower hinged section C⁶ which is adapted to yield as it engages the spacebands so that the finger may ride safely thereover. The hinged lower section C⁶ possesses the additional advantage that, when the line delivery slide is in its receiving position (as in Fig. 1), the section may be readily pushed aside to give access to the line in course of composition for making corrections, etc.
- 15 According to the present invention, and for the reasons before stated, it is preferred to support the hinged section C⁶ from below as well as from above its pivotal axis. Consequently (as best shown in Fig. 4), the upper fixed section C⁴ is formed with a depending tongue C⁵ which extends a substantial distance below the hinge pin c, and the lower section C⁶ is formed with a corresponding vertical slot C⁷ wherein the tongue is snugly confined, the side faces or bearing surfaces c¹ of the tongue contacting throughout their length with the adjacent side walls or bearing surfaces c² of the slot, whereby the bearing surfaces mutually cooperate in rigidly supporting and sustaining the lower section of the finger against edgewise strains or displacement. At its lower extremity, the tongue C⁵ is formed with a banking surface c³ which (as shown in Fig. 4) is beveled upwardly from right to left and against which a similarly beveled bottom wall c⁴ of the slot C⁷ is adapted to engage when the lower hinged section C⁶ occupies its vertical position.
- 20 Although the banking surface c³ may in itself be sufficient to sustain the lower hinged section C⁶ against facewise movement toward the opposing finger C¹, the upper fixed section C⁴ is provided above the hinge c with additional banking surfaces c⁵. These latter banking surfaces, as may be observed, are beveled in the opposite direction and are formed at the lower end of the upper section C⁴ on opposite sides of the tongue C⁵ so as to cooperate with the upper ends of the side

walls c², which latter are beveled to correspond and are adapted to engage therewith as the bottom wall c⁴ of the slot C⁷ comes in contact with the lower banking surface c³.

As a result of the above construction, 70 while the lower section C⁶ may swing freely facewise about the hinge pin c to and from its normal vertical position, it will be rigidly supported and firmly restrained against movement in other directions. Moreover, 75 since the tongue-and-slot connection extends considerably below the hinge, the bearing surfaces presented are greatly increased in extent and permit of a freer and easier swinging movement of the lower hinged section, 80 eliminating all danger of binding.

As a further feature of the invention, the swinging movement of the hinged section C⁶ is yieldingly resisted by a pair of flat springs C⁸, C⁹, which are permanently secured to the upper fixed section C⁴, as by means of clamping screws c⁶, such as are ordinarily employed in attaching the whole finger C² to the slide block C³. These springs serve to hold the hinged section C⁶ 90 normally in its vertical position against the banking surfaces c³, c⁵, and, while their tension is such as to permit the section to yield readily when it is obstructed by a spaceband in the manner before indicated, they are 95 sufficiently strong to sustain it against yielding when the delivery slide is in its receiving position and the lower section C⁶ is called upon to support and guide a composed line of 100 matrices as it is raised to the transfer position. The spring C⁸, as may be observed (see Fig. 3), is considerably shorter than the spring C⁹ and is superposed upon the same so as to supplement the action thereof when 105 the pivotal movement of the hinged section C⁶ becomes pronounced or exaggerated. In this way, the resiliency of the springs C⁸, C⁹ is preserved indefinitely and any danger of the longer spring becoming strained or 110 "set", which might occur if used alone, is avoided. In this connection, it may be stated that the flat type of spring employed 115 is more desirable than springs of other types, since it takes up less room and is not so subject to accidental displacement.

As another feature of the invention, the improved left-hand finger C² is also provided with means in the form of a light leaf spring C¹⁰ for applying a yielding pressure 120 to the matrix line as it is carried upward between the fingers preparatory to its delivery to the casting elevator D. The spring C¹⁰, as will be noted (Figs. 3 and 4) is secured at its lower end to the inner face of the lower hinged section C⁶ and diverges upwardly 125 therefrom to a point opposite the upper section C⁴. Ordinarily, that is, when the composed lines are of the proper length, the spring C¹⁰ is of little or no value and will be cammed aside by the line, but when the

line is excessively short, it acts to straighten up the end matrices if they happen to be tilted or twisted and will thus compact the line and prevent such matrices from falling 5 through the assembler. By locating the spring C¹⁰ on the lower hinged section C⁶, the latter may swing from its normal vertical position without encountering any resistance or interference on the part of the 10 spring.

Having thus describe my invention, what I claim is:

1. In or for a typographical machine, the left-hand finger of a line transfer carriage 15 comprising an upper fixed section and a lower section hinged thereto, the said sections being formed both above and below the axis of the hinge with cooperating non-resilient bearing surfaces, for the purpose described.

2. In or for a typographical machine, the left-hand finger of a line transfer carriage comprising an upper fixed section and a lower section hinged thereto, the said sections being fitted together by an elongated 20 tongue-and-slot connection presenting cooperating non-resilient bearing surfaces extended above and below the axis of the hinge.

3. In or for a typographical machine, the left-hand finger of a line transfer carriage 30 comprising an upper fixed section and a lower section hinged thereto, the said sections being fitted together by an elongated tongue-and-slot connection presenting beveled banking surfaces disposed above and below the axis of the hinge for sustaining the hinged section normally in a vertical position while permitting pivotal movement 35 thereof in one direction.

4. In or for a typographical machine, the left-hand finger of a line transfer carriage comprising an upper fixed section formed 40 with a depending tongue, and a lower section hinged thereto and formed with a vertical slot wherein the tongue engages, said 45 tongue-and-slot presenting long non-resilient bearing surfaces extended above and below the axis of the hinge for the purpose described.

5. In or for a typographical machine, the left-hand finger of a line transfer carriage 50 comprising an upper fixed section formed with a depending tongue, and a lower section hinged thereto and formed with a vertical slot wherein the tongue engages, said tongue 55 presenting long bearing surfaces extended above and below the axis of the hinge and a bottom banking surface for sustaining the said hinged section in its normal position.

6. In or for a typographical machine, the left-hand finger of a line transfer carriage 60 comprising an upper fixed section and a lower section hinged thereto, the said sections being fitted together by an elongated tongue-and-slot connection presenting banking 65 surfaces disposed above and below the axis of

the hinge for limiting the swinging movement of the hinged section in one direction, and a spring secured to the fixed member for resisting such movement of the hinged section in the opposite direction and for maintaining 70 it resiliently in its normal position.

7. In or for a typographical machine, the left-hand finger of a line transfer carriage comprising an upper fixed section, a lower section hingedly connected thereto, positive 75 means for limiting the swinging movement of the hinged section in one direction, and a pair of springs, one serving as a supplement to the other, for resisting such movement thereof in the opposite direction and for 80 maintaining said section resiliently in its normal position.

8. In or for a typographical machine, the left-hand finger of a line transfer carriage comprising an upper fixed section and a lower 85 section hinged thereto, the said sections being fitted together by an elongated tongue-and-slot connection presenting banking surfaces disposed above and below the axis of the hinge for limiting the swinging movement of the 90 hinged section in one direction, and a pair of springs, one serving as a supplement to the other, for resisting such movement thereof in the opposite direction and for maintaining it 95

9. In or for a typographical machine, the left-hand finger of a line transfer carriage comprising an upper fixed section, a lower section hingedly connected thereto, positive 100 means for limiting the swinging movement of the hinged section in one direction, and a pair of flat springs of relatively different lengths for resisting such movement thereof in the opposite direction and for maintaining such section resiliently in its normal position, 105 the shorter spring of said pair being superposed upon the other or longer spring so as to reinforce the latter and supplement the same when the swinging movement of the hinged section is exaggerated. 110

In testimony whereof, this specification has been duly signed by:

ANTHONY J. STOUGES.
